Inventor:

Thomas R. Butman
Forée Bain Esq. May Atty.

UNITED STATES PATENT OFFICE.

THOMAS REED BUTMAN, OF LAKE BLUFF, ILLINOIS.

STEAM-GENERATOR.

No. 866,188.

Specification of Letters Patent.

Patented Sept. 17, 1907.

Application filed December 10, 1906. Serial No. 347,163.

To all whom it may concern:

Be it known that I, THOMAS REED BUTMAN, a citizen of the United States, residing at Lake Bluff, in the county of Lake and State of Illinois, have invented certain new and useful Improvements in Steam-Generators, of which the following is a specification.

My invention relates to improvements in steam generators, and more particularly to generators or boilers of the vertical type.

10 One object of my invention is to provide a boiler having large heating surfaces, simple in form, cheap of construction and highly efficient in operation.

Another object of my invention is to provide, in a boiler, a space shut off from the path of general circulation, into which the water supply shall be first admitted and through which a suitable number of conduits, carrying the exit gases of relatively low temperature shall pass for the purpose of raising the temperature of the feed water therein contained, before it 20 passes into the path of general circulation.

Still another object of my invention is to provide a means for more uniformly distributing the heat to the surfaces of the fire box to prevent the impingement of the heat rays of highest temperature directly upon the 25 flue sheet constituting the top of the fire box.

Other objects of my invention will become apparent to those skilled in the art from the drawings, forming a part of this specification, and from the following description.

30 In the drawings; Figure 1 is a vertical section taken on line 1—1 of Fig. 2. Fig. 2 is a top or plan view, showing a part broken away to expose the fire tubes and the head of the boiler shell below. Fig. 3 is a fragmentary section of a part of the construction, taken on 35 lines 3—3 of Fig. 1.

In all of the views the same numerals of reference indicate similar parts.

5 is an outside shell, containing the head 6, and an annular flue sheet 7.

40 8 is a shell, or cylinder, of smaller diameter, a portion 9 of which extends into the larger shell, to provide a feed-water-containing space between the outer shell and the said cylinder, as shown in the drawings. The inner shell, or cylinder, is joined to the outer shell by 45 the annular flue sheet 7 in the manner shown. The inner shell, or cylinder, is connected to the fire box by means of the annular concave head 10 providing thereby a settling chamber or mud container in the bottom of which a blow-off pipe 11 is placed.

50 The side walls of the fire box 12 is preferably corrugated for the purpose of providing slight vertical movement, due to expansion and contraction, as usual in such cases. The flue sheet 13, affording a top for the fire box, is perforated for the admission of fire tubes 55 14, which are suitably grouped around the axis of the

boiler, in the manner shown more clearly in Fig. 2, to provide spaces for admission of the boiler braces 15. The upper ends of the fire tubes 14 are expanded into the head 6 of the shell 5. The tubes 14 are spread at the top, as shown, to provide a space 16 for the admission of the steam discharge pipe 17, and for the further purpose of providing the openings necessary for the brace bars 15, as heretofore described. Return fire tubes 18 are also expanded into the head 6, and extend through the space, which I have heretofore referred to 60 as the feed-water-containing space, the lower ends of which are expanded into the annular flue sheet 7, the said tubes terminating in a fire box, or flue, 18', which in turn communicates with the breeching, or smoke pipe 19. To the upper part 9, of the cylinder 8, is attached a series of vertically extending tie-bars 20 which are connected to the upper part 9, of the cylinder 8, and also to the head 6 of the shell 5, to bear a part of the strain that would otherwise come on the shell 5 and the tubes 14, and to relieve the fire box of undue strain. 75

The space between the upper part 9 of the cylinder 8 and the shell 5, into which the feed water supply is to be admitted primarily, functions in every respect similar to well known "economizers," which are devices usually used in association with steam boilers 80 by means of which the uptake, or exit gases, are employed for heating the feed water before it is admitted into the path of circulation of the boiler. In this instance the economizer device becomes a part of the boiler, in which the water is heated by means of the 85 hot exit gases just before they leave the boiler, the water being confined so as not to be permitted to enter the path of general circulation until its temperature has been sufficiently raised.

In the bottom of the annular feed water chamber, 90 just described, is placed a blow-off pipe 21, for blowing off the settling or mud that might otherwise remain in the chamber and become detrimental to its use. A feed water pipe 22 is shown, by means of which the water, to be supplied to the boiler for steam making 95 purposes, is admitted into the feed water space. Hand-holes 23 are made into the outer shell 5 at suitable intervals for the purpose of cleaning the economizing chamber, or the annular space intervening between the upper part 9 of the cylinder 8 and the shell 5. In 100 Fig. 2 it will be noted that certain of the tubes 18 have been left out on either side of the manhole 24 for the purpose of providing room for the entrance of persons in attendance, within the shell 5 of the boiler, for convenient cleaning and for repairs of the boiler.

105 25 is a fragmentary portion of the furnace, showing a passage way for the gases to enter the fire box 12. In the center of the fire box is a pier 26 of relatively refractory material, such as fire brick, or made of a series of disks of fire brick clay, properly baked, or 110

- other heat-absorbing and refractory material, the object of which is to absorb the heat from the direct and intense rays and subsequently disperse it against the vertical sides of the fire box, whereby a more uniform 65
- 5 distribution of heat is accomplished and the direct impingement of the intense blast is prevented from injuring the flue sheet into which the tubes 14 enter.
- My boiler is adapted to receive the hot gases from any source of heat. Where a special furnace is to be 70
- 10 constructed one of the Dutch-oven variety is well adapted to its use. Or the hot gases arising from any other source, such as a puddling furnace may be directed into the fire box and utilized in the desired manner.
- 15 27 is a smoke box for conducting the hot gases of combustion from tubes 14 to the return tubes 18. The heated gases from any source may be conducted into the fire box 12, from whence they will pass through the series of tubes 14 into the smoke box 27, from thence 75
- 20 to the annular smoke box 18' by means of the fire tubes 18, and thence to the smoke stack by means of the breeching or smoke pipe 19. As heretofore stated, the gases of lowest temperature will pass through the tubes 18 and heat the water contained in the space between 80
- 25 the upper part 9 of the cylinder 8 and that portion of the shell before it mixes with the steam-making water. 85
- The use and operation of my invention will be well understood by those skilled in the art.
- While I have herein described, in some detail, a 90
- 30 specific embodiment of my invention, I do not desire to be limited to the exact construction shown in the drawings, as considerable variation may be made without departure from the spirit and scope of my invention.
- Having thus described my invention, what I claim 95
- 35 and desire to secure by Letters Patent, of the United States, is:
1. A vertical steam boiler comprising a shell, a fire box within said shell, an open-ended annular cylinder, between said fire box and the shell extending above said fire box to 100
  - 40 box to provide an annular feed-water space between said shell and cylinder, a series of fire tubes communicating with said fire box and extending through said shell, a series of return fire tubes annularly arranged and passing through said shell in the annular space provided between 105
  - 45 said shell and cylinder, and a water feed pipe communicating with said feed-water space.
  2. A vertical steam boiler comprising a shell, a fire box within said shell, an open-ended annular cylinder between said fire box and shell extending above said fire box to 110
  - 50 provide an annular feed-water space between said shell and cylinder, a series of fire tubes communicating with said fire box extending through said shell and spaced further from the axis of the boiler at the top than at the bottom, a series of return fire tubes annularly arranged and 115
  - 55 passing through said shell in the annular space provided between said shell and cylinder, and a water feed pipe communicating with said feed-water space.
  3. A vertical steam boiler comprising a shell, a fire box within said shell, an open-ended annular cylinder between 120
  - 60 said fire box and shell, extending above said fire box to provide an annular feed-water space between said shell and cylinder, a series of fire tubes communicating with said fire box and extending through said shell, a steam discharge opening communicating with the axial space so 125
- provided near the top of the shell, a series of return fire tubes annularly arranged and passing through said shell in the annular space provided between said shell and cylinder, and a water feed pipe communicating with said feed-water space.
4. A vertical steam boiler comprising a shell, a fire box 70
- within said shell, an open-ended annular cylinder between said fire box and shell extending above said fire box to provide an annular feed-water space between said shell and cylinder, a series of return fire tubes annularly arranged and divided into groups, or sections, to provide 75
- spaces at intervals for brace rods, brace rods within said spaces extending from the side walls to the head of the shell.
5. A vertical steam boiler comprising a shell, a fire box 80
- within said shell, an open-ended annular cylinder between said fire box and shell extending above said fire box to provide an annular feed-water space between said shell and cylinder, a series of return fire tubes annularly arranged and divided into groups or sections, to provide 85
- spaces at intervals for brace rods, brace rods within said spaces extending from the side walls to the head of the shell, a man hole in said shell opening into one of said spaces between contiguous groups or sections of said tubes.
6. A vertical steam boiler comprising a shell of larger 90
- diameter, a shell of smaller diameter open at its top end and extending into said shell of larger diameter to a point above the top of the fire box, a fire box within the smaller shell, an annular flue-sheet joining the two shells at the lower end of the large shell, a series of fire tubes communicating with said fire box and extending through said 95
- larger shell, a series of return fire tubes annularly arranged and passing through the head of the said larger shell and the said annular flue sheet, and an annular smoke box surrounding the said smaller shell.
7. A vertical steam boiler comprising a shell of larger 100
- diameter, a shell of smaller diameter open at its top end and extending into the said shell of larger diameter to a point above the top of the fire box, vertical brace-rods spaced at intervals and tying the upper end of the said smaller shell to the head in the upper end of the large shell, a fire box within the smaller shell, and an annular flue sheet joining the two shells at the lower end of the 105
- larger shell.
8. A vertical steam boiler comprising a shell of larger 110
- diameter, a shell of smaller diameter open at its top end and extending into the said shell of larger diameter to a point above the top of the fire box, a fire box within the smaller shell, an annular sheet joining the two shells at the lower end of the larger shell, a water feed pipe communicating with the annular space between the two shells, 115
- fire tubes passing through the said annular space, and a blow-off pipe located in or near the bottom of the said space.
9. A vertical steam boiler comprising a shell, conduits 120
- through the shell for conducting the heated gases, an open-ended cylinder extending upwardly from the bottom of the shell intermediate the said conduits and the side walls of the said shell, and other conduits for the passage of the heated gases within the space between the said cylinder and shell.
10. In a vertical steam boiler, a fire box having a top flue sheet, a surrounding shell, fire tubes opening through the flue sheet and extending through the shell, and a pier of relatively refractory material extending axially into the fire box for imparting heat to the vertical side walls 130
- of said fire box.
- In testimony whereof I hereunto set my hand in the presence of two witnesses.
- THOMAS REED BUTMAN.
